UNITED STATES PATENT OFFICE.

CALVIN G. LINDSAY, OF LEXINGTON, ILLINOIS.

GATE.

No. 823,692.

Specification of Letters Patent.

Patented June 19, 1906.

Application filed January 22, 1904. Serial No. 190,192.

To all whom it may concern:

Be it known that I, CALVIN G. LINDSAY, a citizen of the United States; residing at Lexington, in the county of McLean and State of Illinois, have invented a new and useful Gate, of which the following is a specification.

My invention relates to gates, and especially to the gate-operating mechanism, and has for its objects to produce a comparatively simple inexpensive device of this character whereby the gate may be readily opened or closed and automatically locked in either of said positions, and one in which the gate-locking members will be positively released at the beginning of the gate-moving operation.

To these ends the invention comprises the novel features of construction and combination of parts more fully hereinafter described.

In the accompanying drawings, Figure 1 is a side elevation of a gate and its operating mechanism embodying my invention. Fig. 2 is an end elevation of the same.

Referring to the drawings, 1 designates a supporting-frame comprising a pair of end posts or standards 2, an intermediate post 3, and a top connecting-bar 4, extended between and attached in any appropriate manner to the upper ends of the posts, there being sustained by said frame an overhead track or way 5.

Suspended from the track 5 by means of end hangers 6, having at their upper ends anti-friction-rollers 7, designed for travel upon the track, is a gate 8, comprising bars 9 and horizontal slats or rails 10, there being pivoted to the gate, respectively at opposite ends thereof, a pair of latch members 11 12, designed to swing in a vertical plane for engagement with or disengagement from suitable keepers 13, carried, respectively, by the front and rear end posts 2 of the frame, the latches being normally pressed to engaging position for automatic engagement with their keepers by means of springs 14.

Arranged upon opposite sides of the gate at points suitably remote therefrom and in line with the central post 3 is a pair of supports 15, having at their upper ends suitable bearings for the reception of a horizontal rotary operating-shaft 16, supported between its ends by a bearing 17, carried by the post 3; said shaft having fixed, respectively, upon its opposite ends a pair of operating members or crank-wheels 18, and between its ends in alinement with and immediately over the top rail of the gate 8 a winding-drum 19. It is to

be noted that under this construction the shaft may, through the medium of the crank-wheels 18, be readily actuated at points remote from and on either side of the gate, by a person seated upon horseback or in a vehicle and without dismounting.

Suitably coiled around the drum 19 is an operating-cable or its equivalent 20, which extends in opposite directions from the drum 65 through suitable guides 21, carried by the top rail of the gate adjacent to the opposite ends of the latter, and has its terminals attached in some appropriate manner respectively to the latch members 11 12, it being apparent 70 that as the drum is rotated with the shaft in the manner above explained the cable will be wound thereon in one direction and payed off in the other, thus positively moving the gate to open or closed position according to 75 the direction of rotation of the drum.

During the travel of the gate it will be prevented from lateral oscillation, and thus caused to move steadily and evenly by means of a bearing-roller 22, sustained by a suitable 80 bracket at the lower end of the post 3 in position to engage the lower horizontal rail 10.

In practice the gate will be automatically locked in its open or closed position by the latches 11 12, respectively, and these latches 85 will—that is, the one which is in active engagement will—be positively released through the medium of the cable 20 at the beginning of the gate opening or closing movement. It is to be particularly noted in 90 this connection that the one cable performs the three-fold function of moving the gate to open or closed position and independently operating a pair of latches designed to lock the gate in either of said positions. 95

From the foregoing it will be seen that I produce a comparatively simple inexpensive device admirably adapted for the attainment of the ends in view, it being understood that minor changes may be resorted to without 100 departing from the spirit of the invention.

Having thus described the invention, what is claimed is—

In a gate the combination with an intermediate and end standards, and a track supported by the standards; of a gate, hangers extending therefrom and movably mounted upon the track, latches pivotally connected at their inner ends, to the gate and projecting beyond the ends of the gate, a coiled spring 105 interposed between each latch and the top rail of the gate, eyes carried by the top rail of

the gate at points between its ends, a shaft journaled upon the intermediate standard and extending to opposite sides of the gate, hand-wheels for rotating the shaft, a drum upon the shaft and between the intermediate standards and the path of the hangers, said drum overlapping and disposed close to the top rail of the gate, and a cable wound upon

the drum and extending over one side of and shielded by the top rail of the gate, the ends of said cable being movably mounted within the eyes and secured to the latches.

C. G. LINDSAY.
